UNITED STATES PATENT OFFICE.

JOHN LEWIS PERKINS AND ELLEN M. PERKINS, OF HOLYOKE, EXECUTORS OF BENJAMIN F. PERKINS, DECEASED, AND CHARLES E. POPE, OF SOUTH HADLEY, MASSACHUSETTS; JOHN LEWIS PERKINS CONSERVATOR OF SAID ELLEN M. PERKINS, INCAPACITATED.

PAPER-REELING MACHINE.

SPECIFICATION forming part of Letters Patent No. 739,712, dated September 22, 1903.

Application filed February 2, 1903. Serial No. 141,628. (No model.)

To all whom it may concern:

Be it known that BENJAMIN F. PERKINS, deceased, late of the city of Holyoke, in the county of Hampden, and CHARLES E. POPE, of South Hadley, in the county of Hampshire, State of Massachusetts, did during the lifetime of said BENJAMIN F. PERKINS invent a new and useful Improvement in Paper-Reeling Machines, and that JOHN LEWIS PERKINS, a citizen of the United States, and a resident of Holyoke aforesaid, having been duly constituted and appointed one of the executors of the estate of said BENJAMIN F. PERKINS, deceased, and having been duly constituted and appointed conservator of and for ELLEN M. PERKINS, incapacitated, the other executor of the estate of said BENJAMIN F. PERKINS, deceased, and said CHARLES E. POPE, do hereby declare that the following is a full, clear, and exact description of said invention.

This invention relates to improvements in machines for reeling paper, the paper being run onto the rotary reel from a plurality of supply-rolls; and the object of the invention is to have the reel constituted an automatic counter, so that clearly-defined series or sets of the convolutions of the paper on the reel may be perceived, and whereby therefore when the paper is cut in a straight line parallel with the axis of the reel and all the paper which had been wound thereon removed therefrom and laid out in a flat condition every twelve sheets thereof or other number, as predetermined, will be edgewise slightly offset from the next twelve or other desired number of the sheets.

The improved machine comprises a reeling-frame for the paper mounted for rotation and having rotating means therefor and susceptible of a periodical reciprocatory motion on the line of its axis and having combined therewith means for imparting once to every given number of turns of the reel the proper degree of endwise motion to the latter.

The improved reel is illustrated in the accompanying drawings, in which—

Figure 1 is a side elevation of the reel and the supports for a plurality of paper-supply

rolls and such rolls mounted thereon. Fig. 2 is a front elevation of the reel, portions being broken out and shown in section for clearer illustration. Fig. 3 is a perspective view of the preferred form of cam employed in the mechanism which offsets the reel in a reciprocatory manner relatively to the fixed positions of the paper-supply rolls.

Similar characters of reference indicate corresponding parts in all of the views.

In the drawings, A represents the supporting-frame for a plurality of supply-rolls *a* for tissue or other paper, and B represents the supporting-frame for the reel C. The end journals of the supply-rolls have thereon sheaves or fixed wheels *b*, around which are the straps *c*, connected to a stem *c*², which is screw-threaded and passed through a perforation in a stud *c*³, affixed on the frame, the thumb-nut *d* screwing and drawing on the stem and resisted by the stud serving to place the strap in proper tension for its required frictional action upon the sheaves fixed on the arbors of the paper-supply rolls.

The reel, as shown, is constituted by a plurality of bars *f*, arranged in parallelism with the axis of the reel and supported from the reel-shaft *g* by the radial duplicated arms *f*². The reel-shaft *g* is rotatable in the journal-bearings *i* of the frame B, and this shaft is also capable of a suitable degree of endwise movement in and through said journal-bearings.

E represents the driving-shaft, having loose and fixed driving-pulleys thereon and having the pinion-wheel *j*, which is in mesh with the gear-wheel *j*², affixed on the end of the reel-shaft *g*. Upon the reel-shaft *g* is affixed a circular hub *k*, which is provided with a comparatively wide annular groove *m*, in which engages the cams *o*, which are formed on or carried by the disk or wheel *q*, affixed upon the short counter-shaft *q*², having thereon the gear-wheel *s*, which is in driving engagement with the comparatively long pinion *t* on the reel-shaft.

The reel, which is rotated from the main shaft, in turn rotates the counter-shaft and
